NATHAN LAWRENCE, OF TAUNTON, MASSACHUSETTS, ASSIGNOR
TO REED AND BARTON, OF SAME PLACE.

Design No. 3,375, dated February 16, 1869.

DESIGN FOR AN ICE-PITCHER.

The Schedule referred to in these Letters Patent and making part of the same.

To all whom it may concern:

Be it known that I, NATHAN LAWRENCE, of Taunton, in the county of Bristol, and State of Massachusetts, have originated a Design for a Double-Wall Ice-Pitcher, of which the following is a full, clear, and exact description, reference being had to the accompanying drawings, making part of this specification.

Figure 1 is a side view.

Figure 2, a plan.

This invention consists in the peculiar form of a double-wall ice-pitcher, hereinafter described, said form being given to the body of the pitcher alone, and being employed for ornamental purposes, and to distinguish ice-pitchers, of the inventor's manufacture, from all others.

The form which I thus employ, and which is clearly represented in figs. 1 and 2, is the oval or elliptical

form; or, to speak more accurately, it consists in so constructing the body, A, of the pitcher, that if a horizontal section be taken through the same, at any point, said section will show two skeleton ellipses, one being the inner, and the other, the outer wall of the pitcher. At the same time, as seen in the plan, fig. 2, both the bottom, B, and the cover C, are necessarily of a similar shape.

Having thus described my invention,

What I claim as new, and desire to secure by Letters Patent, is—

The design, of an oval shape, when applied to the body of a double-wall ice-pitcher.

NATHAN LAWRENCE.
